(57) **CLAIM**

The ornamental design for a bottle sterilizer and dryer, as shown and described.

DESCRIPTION

FIG. 1 is a top, front, left side perspective view of a bottle sterilizer and dryer showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a bottom, rear, right side perspective view thereof; and,
FIG. 9 is an alternative perspective view of the bottle sterilizer and dryer when there is only one container.
The broken lines show features of the bottle sterilizer and dryer that form no part of the claimed design.

1 Claim, 9 Drawing Sheets
